STRAP TENSIONING AND SEALING DEVICE

Herman J. Spencer, West View, Pa., assignor to
 Leechgrip Company, O'Hara Township, Alle-
 gheny County, Pa., a corporation of Pennsyl-
 vania

Application August 11, 1937, Serial No. 158,600

10 Claims. (Cl. 81—9.1)

The present invention relates to a device for securing together the ends of a metallic reinforcing strip or band which has been passed around a container or package and more particularly to certain improvements in a device of such character such as the one shown and described in my co-pending application Serial No. 23,895, filed May 28, 1935, now Patent Number 2,102,981, dated December 21, 1937.

10 While devices of this general character have been known heretofore those with which I am familiar are characterized by certain objectionable features. The purpose of the present invention is to produce a strap fastening device 15 which is characterized by simplicity, relatively low cost of construction, a high degree of effectiveness in operation, and which requires little or no maintenance. Other novel features and advantages of the present invention will be more 20 specifically pointed out and described in the detailed description of the preferred embodiment of my invention which is illustrated in the appended drawings.

In accordance with my invention, I provide a 25 device having a base and a standard mounted thereon, the base and standard carrying the various operating parts. The structure is provided with three operating handles or levers by which all of the necessary operations are carried out.

30 One handle or lever is arranged to actuate rollers for tightening the band or strap around the box or package. A second lever cooperates with the tightening mechanism and is adapted to lower the toothed wheels which are used for tightening 35 the strap down onto the strap and for raising the wheels after the completion of the strapping operation. This same lever is also so arranged as to operate the feeding mechanism for feeding a clip or seal into appropriate position above the overlapped ends of the strap. This same lever is 40 also arranged so that it can be operatively disengaged from the tightening mechanism and swung in the reverse direction for cooperation with a lever for actuating a shear for cutting off the coil end of the strap. The third lever is the 45 forming lever. This lever actuates the mechanism comprising a ram and forming jaws. Operation of the forming lever causes the ram to descend in the standard and as it descends the 50 forming jaws are adapted to bend a flat clip seal around the overlapping ends of the strap, and continued downward movement of the ram crimps the clip seal and the strap ends so as to form a permanent joint therebetween.

55 A device of this general character is shown and

described in my copending application Serial No. 23,895. While the device there shown and described obviates many of the difficulties of the machines known heretofore the device which I provide by my present invention obviates certain 5 difficulties encountered with that machine as well as in the prior art machines. In the prior art machines the coil end of the strap has of necessity been cut or sheared some little distance away from the seal. This leaves a free and exposed 10 strap end which bends upwardly to a slight extent from the end of the seal and presents a hazard to the person handling the bundle, box or package which has been strapped. The straps used are quite thin but they are sufficiently rigid that the 15 free exposed strap end will do substantial damage either to the hands of the person handling the box or bundle or to articles with which it may come in contact. By the present invention I provide a structure which overcomes this difficulty 20 and which permits the cutting of the coil end of the strap at the exact edge of the seal or beneath the seal so that there is little or no free exposed 25 strap end which may cause damage.

In accordance with the present invention I also 25 provide a structure in which difficulties in feeding the flat clip blank over the overlapping strap ends are overcome. In the structure which I provide the feeding mechanism for feeding the flat 30 clip blanks from the magazine which contains a plurality of them is actuated by the lever which is used for bringing the tightening wheels into contact with the overlapping strap ends. The feeding mechanism is of such character that the feeding shuttle and the pawl carried thereby will 35 not be retracted by the feeding mechanism unless the shuttle lever has been actuated to such an extent as to properly position the flat clip seal over the overlapping ends of the strap. For example, if the feeding shuttle and the pawl carried 40 thereby are only moved throughout a portion of the distance required to completely feed the flat clip blanks, the shuttle will remain in this position until the shuttle lever is moved to a sufficient extent to complete the feeding operation. This is highly advantageous in structures 45 of this character as it precludes any possibility of feeding more than one flat clip seal to crimping position at any one time and it also prevents jamming of the device.

50 Another feature of the present invention resides in the provision of positive seal supporting members for supporting the flat clip seals on the bottom of the presser head. In accordance with my invention I provide seal supports for engaging 55

the ends of the flat clip blank for supporting the blank above the strap ends until the ram and the presser head are lowered onto the overlapping strap ends for the formation of a seal.

5 Another feature of the present invention resides in the provision of a spring pressed pin extending through the base of the presser head and cooperating with a small hole or recess in the flat clip seal for positively centering the seal 10 so that it will be in proper position when lowered onto the overlapping strap ends.

For a complete understanding of the present invention, reference is made to the accompanying drawings illustrating a present preferred embodiment, although it will be understood that numerous details shown and described may be otherwise embodied without departing from the scope of my broader claims.

In the drawings,

20 Figure 1 is a side elevational view of the structure which I provide placed in operative position upon a box about which the strap has been passed;

25 Figure 2 is a plan view, partly in section, of the structure shown in Figure 1;

Figure 3 is an end elevational view of the structure in Figure 1, a portion of the feeding mechanism being shown in section;

30 Figure 4 is a transverse section taken along the line IV—IV of Figure 2;

Figure 5 is a longitudinal sectional view taken along the line V—V of Figure 2;

Figure 6 is an enlarged partial sectional view taken along the line VI—VI of Figure 2;

35 Figure 7 is an elevational view of the cutting mechanism;

Figure 8 is a plan view of the cutting mechanism shown in Figure 7;

40 Figure 9 is a perspective view of one of the supports for holding the flat clip seals in position on the base of the presser head;

Figure 10 is a plan view of the joint formed by the device which I provide;

45 Figure 11 is a side elevational view of the joint shown in Figure 10; and

Figure 12 is a section taken along the line XII—XII of Figure 10.

Referring to the drawings, the device comprises a base 2 having a standard 3 mounted thereon. 50 The standard 3 is split along a substantially central plane as indicated at 4, for convenience in assembling, into two portions 5 and 6 which are appropriately secured together by means of screws 7 and 8. The portion 6 of the standard is 55 secured to and supported on the base 2. The portion 5 of the standard is carried on the portion 6 in overhanging relation to one edge of the base 2 which is tapered or feathered off at 9 to facilitate the entry of such edge under the meeting ends of 60 a metallic strap or band 10 passed around a box or package 11. The tapered edge of the base 2 is slotted at 12 for a purpose which will presently appear.

65 In use the strap 10 is drawn from a coil 13 and wrapped around the box 11 and the free end brought back under the portion of the strap extending to the coil as shown in Figure 1. The device is then moved so that the tapered edge of the base 2 enters under the free end of 70 the strap. The coil end of the strap is disposed between a shearing block 15 and the shear 16. The shear 16 is normally upraised so as to permit the strap to be positioned between it and the shearing block, but is reciprocable relative 75 to the shearing block 15 so as to permit the

shearing of the coil end of the strap. This shearing mechanism will be described more in detail later. Keepers 17 and 18 are provided for holding the overlapped ends of the strap in proper position for joining them together. The keepers 17 and 18 are pivotally mounted on the standard 3. The keeper 18 is manually operable and the keeper 17 is automatically operated by the mechanism for feeding the flat clip blanks into position over the strap ends. This operating mechanism will be described more in detail later.

Before shearing the coil end of the strap from that portion which has been passed around the box 11, it is desirable to tighten the strap around the box and to hold it in tension during the formation of the joint so that a tight strap will be formed about the box. A lateral extension 23 of the standard provides support for the mechanism for tightening the strap about the box. An eccentric shaft 24 is mounted for rotation in the lateral extension 23. The eccentric shaft 24 extends completely through the extension 23. The one end of the shaft 24 is enlarged as at 25 and the enlarged portion is provided with slots 26 which are adapted to cooperate with laterally projecting prongs or fingers 27 at the lower end of the eccentric shaft lever 28. The eccentric portion 29 of the shaft 24 between the enlarged portion 25 and the standard 23 carry toothed tightening wheels 30 which are free to rotate relative to the shaft. A ratchet wheel 31 is provided between the toothed wheels 30 and rigidly secured to the wheels 30 by rivets 32.

The eccentric shaft lever is hinged intermediate its length on a hinge pin 33 which is supported by the shear lever 34 more specifically described hereinafter. At its upper end the shaft lever is bent to cooperate with the cam end 35 of the operating handle 36 which is mounted for rotation about a fulcrum pin 37 carried by the 40 shear lever 34. This arrangement is provided in order to permit the disengagement of the shaft lever from the eccentric shaft so as to permit the shaft lever and the shear lever which carries it to be rotated without rotation of the eccentric shaft. 45

In order to disengage the shaft lever it is merely necessary that the handle 36 be rotated about the fulcrum pin into the position shown in dotted lines in Figure 6. As the handle is moved to this position the cam surface of the handle 50 operates with the upper end of the shaft lever and rotates the shaft lever about its hinge pin, thereby moving the shaft lever to the position shown in chain lines in Figure 6. In this position the fingers 27 are completely removed from the slots 26 so that rotation of the shear lever and the shaft lever will not result in rotation of the eccentric shaft and the parts carried thereby.

The shaft lever is normally forced to the position shown in solid lines in Figure 6 by a flat 60 steel spring 38 which is secured to the frame 39 of the shear lever. At its lower end the spring is bent inwardly so as to bear against the lower end of the shaft lever and force it into operative relationship with the eccentric shaft. 65

The shear lever 34 is carried by the eccentric shaft, it being supported on the end of the eccentric shaft by means of a screw 40 which is threaded into the threaded opening 41 in the end of the shaft. The screw 40 is provided with a supporting surface 42 upon which the shear lever is mounted. The shear lever is provided with openings 43 through which the fingers of the shaft lever extend for engagement with the slots in the eccentric shaft.

The eccentric portion of the shaft 24 also carries ratchet retaining plates 44 on either side of the toothed wheels 30. These ratchet retaining plates are securely connected at their upper ends with a handle 45 which carries a grip 46 on the outer end thereof. An operating pawl 47 is mounted on a pin 48 carried between the ratchet retaining plates. This pawl cooperates with the ratchet wheel 31 for rotation of the ratchet wheel and the toothed band tightening wheels upon movement of the handle 45. The pawl, upon movement of the handle 45 in a counter-clockwise direction as shown in Figure 5, slides over the teeth of the ratchet wheel and upon movement of the lever in a clockwise direction engages the teeth and causes rotation of the wheel. A pawl spring 49 is positioned in a recess 50 in the ratchet lever 45 and cooperates with the pawl for normally forcing it into engagement with the ratchet teeth.

A pawl 51 is pivotally mounted on a pin 52 carried by the standard adjacent the ratchet wheel. This pawl cooperates with the ratchet wheel so as to prevent rotation of the ratchet wheel in a counter-clockwise direction as shown in Figure 5. The pawl 51 is normally urged into engagement with the teeth of the ratchet wheel by a spring 53, one end of which is supported in a recess 54 in the standard and the other end of which cooperates with a pin 55 carried by the pawl 51.

It will be seen from the above that rotation of the eccentric shaft by the eccentric shaft lever will move the toothed wheels into engagement with the over-lapped strap ends positioned therebelow. The toothed wheels are positioned immediately above a serrated insert 56 over which the strap ends pass. As will be apparent, if the toothed wheels 30 have been brought into engagement with the overlapping strap ends, the ratchet lever 45 can be reciprocated and the strap ends tightened around the package or bundle about which the strap is placed.

After adequate tightening has been effected, the handle 36 is moved to the position shown in chain lines in Figure 6 and the shaft lever disengaged from the shaft so that the shear lever maybe rotated for effecting the shearing operation without rotation of the eccentric shaft.

When the strap has been tightened around the box as described above, the free end is ready to be attached permanently to the coil portion of the strap, and the coil portion of the strap sheared from the body of the coil. I utilize a substantially flat rectangular sheet metal clip for effecting the joint between the overlapped strap ends. The clip seals which I use are adapted to have their edges bent around the strap and crimped so as to permanently bind the two ends of strap against relative movement.

A supply of the clip blanks 61 is maintained in a magazine 62 mounted on the standard 3. The magazine 62 comprises a sheet metal channel 63 which is provided with a removable cover 64 to permit the insertion of additional clip blanks 61 therein. A seal retaining member 65 cooperates with the uppermost seal in the magazine. A spring 66 cooperates with the upper end of the magazine and with the retaining member 65 so as to normally force the seals which are in the magazine in a downward direction so that the lowermost one will be in position to be fed over the superposed strap ends.

The feeding of the clips from the magazine to a position over the strap is effected through rotation of the eccentric shaft 24. A collar 67 is

secured to the outer end of the shaft by means of a set screw 68. This collar is provided with a pin 69 adapted to cooperate with a slot 70 in the shuttle lever 71 which is pivotally mounted on the base 2 by means of a screw 72. The shuttle lever 71 comprises a main body portion 73 and an end portion 74. The end portion 74 is pivotally mounted on a pin 75 extending through openings 76 in depending lugs 77 on the main body portion of the shuttle lever. A spring 78 surrounds one end of the pin 75 and one end abuts against the lug 77 and the other end abuts against the end portion 74. By this arrangement the end portion 74 of the shuttle lever may be raised or lowered about the pin 75 and due to the resilient mounting it will remain in any position to which it is moved. Another feature of this type of mounting for the operating end of the shuttle lever is that it provides an adjustment for the shuttle lever so that it can be adjusted laterally in order to provide for proper feeding of the seals. This is of substantial importance where seals of different sizes are utilized.

The operating end 74 of the shuttle lever is adapted to cooperate with the reciprocable shuttle 79 mounted within a shuttle guard 80 which is positioned under the casing 81 which is mounted on the base of the device. The operating end 74 of the shuttle lever extends through an opening 82 in the adjacent side wall of the casing 81 and through a longitudinal recess 83 in the shuttle guard. It extends into the L-shaped recess 84 in the shuttle so that it will operate the shuttle in both the feeding direction and in the reverse direction. One side of the opening 84 presents a relatively long cooperating face 85 for cooperation with the lever 74. The other face of the opening or recess 84 is shorter than the face 85 so as to provide the L-shaped recess extending through the rear end of the shuttle and to present a shoulder 86 which will not be engaged by the operating lever 74 when it has been moved to its lowermost position.

In normal non-operating position the parts are as shown in Figure 4, the operating end of the shuttle lever being so positioned that movement thereof in the feeding direction will cause the shuttle 79 to move forward and movement of the operating lever in the reverse direction will cause it to pass beneath the face 86 of the recess 84.

Actuation of the shuttle is effected by rotation of the eccentric shaft 24. As it is rotated the pin 69 is moved in the operating slot 70 in the shuttle lever and the operating end of the shuttle lever cooperates with the face 85 and moves the shuttle and the shuttle pawl 87 carried thereby forwardly. The shuttle pawl is mounted on a shaft 88 carried by the shuttle and a spring 89 is provided for normally urging the forward end of the pawl in an upward direction. A stop pin 90 is also provided on the shuttle pawl which is adapted to cooperate with the upper end of the shuttle in order to prevent the spring from forcing the forward end of the pawl too far upwardly. As the shuttle and the shuttle pawl are moved forward, the forward end of the pawl passes the end 91 of the shuttle guard and is forced upwardly to a sufficient extent to permit the forward end of the pawl to engage the lowermost seal in the magazine. Continued movement of the shuttle 79 in a feeding direction will cause the seal 61 to be carried to a position above and to be properly positioned over the overlapped ends of the strap 10.

A resilient spring 92 is mounted on the base

adjacent the magazine for the seals. The outermost end of the spring 92 is secured to the base and the inner end which is positioned adjacent the magazine is bent upwardly as indicated at 93. 5
 5 As the shuttle moves forward in a feeding direction, the operating end 74 of the shuttle lever is in the position indicated in Figure 4. If sufficient movement of the operating lever is not effected to complete the feeding operation and the shuttle lever is moved in the reverse direction, due to 10
 10 the fact that it is in the lower position it will not engage the shoulder 86 of the shuttle and the shuttle itself will not be returned to non-operating position. However, if the shuttle lever is moved through its entire feeding stroke, when it 15
 15 reaches the forward end thereof the spring 92 will raise the operating end of the shuttle lever upwardly to the position where it will engage the shoulder 86 of the shuttle so that upon the 20
 20 return stroke of the shuttle lever the shuttle will be returned to rest position.

As the operating end of the shuttle lever is in raised position during the return stroke it is desirable before it reaches the end of the return 25
 25 stroke to force the shuttle lever to the lowered position so that the apparatus will again properly function during the feeding operation. The shuttle guard is provided with a member 94 having a shoulder 94a adjacent the end thereof so 30
 30 that at substantially the termination of the return stroke of the shuttle lever the shoulder will cooperate with the shuttle lever to move it downwardly to its lowermost position. As the shuttle lever is moved rearwardly it is in the upper position 35
 35 in which it engages the shoulder 86 of the shuttle. Near the end of the return stroke the lever comes in contact with the inclined shoulder 94a and is cammed to the lower position.

The shuttle lever, the shuttle and the operating mechanism just described, are arranged in 40
 40 this way so that if the shuttle is not moved completely through the feeding stroke movement of the shuttle lever to the left as shown in Figure 4 will not move the shuttle back to a position where it can engage and move forward another 45
 45 flat clip blank upon further movement of the shuttle lever in the feeding direction. If the parts were not constructed and arranged in this manner, one flat clip blank could be fed only part way toward the sealing mechanism and another 50
 50 flat clip blank could also be fed forward and jamming of the machine would result. As the parts are arranged if a flat clip blank is only fed through a portion of the feeding stroke due to incomplete movement of the shuttle the movement 55
 55 of the shuttle lever through the return stroke will not return the shuttle. Before any additional clip can be fed into position beneath the sealing mechanism the one which has been partially moved forward will have to be moved 60
 60 through the complete feeding stroke. As the parts are arranged the shuttle lever will not return the shuttle to a position where it can pick up an additional flat clip seal until the feeding stroke has been completed. Feeding mechanism 65
 65 of this character is advantageous as it precludes any possibility of jamming and also precludes any possibility of more than one clip seal being fed over the superposed strap ends at any one time.

After the strap has been tightened in the 70
 70 manner heretofore described, it is desirable to cut the coil end of the strap from the remainder thereof. In accordance with my invention I provide a cutting or shearing device which is movable so that it can be moved to a position be-

neath the bending and crimping mechanism and effect the shearing adjacent the edge of the seal or beneath the edge of the seal or at least sufficiently close to the edge of the seal that an insufficient amount of free strap end will be left 5 exposed to do any damage. The shear or cutting mechanism consists of a shear block 15, a top shear 16, a shear operating lever 95, and a shear frame 96. The shear frame and the other portions of the shear mechanism are mounted on 10 the base 2 of the device and are movably secured thereto by means of the shear frame pin 97. The top shear 16 is provided with a shearing edge 98 which is adapted to cooperate with the shearing block. The top shear is fulcrumed on 15 the shear frame by a pin 99 for movement relative to the cutting block. The shear operating lever 95 is pivotally mounted on the shear frame by the fulcrum pin 100. A spring 101 is provided for normally urging the top shear upwardly out 20 of cutting position. A second spring 102 is provided for normally urging the shear frame and the parts described above toward shearing position, one end of the spring 102 cooperating with an abutment on the base 2 and the other end 25 thereof cooperating with the shear frame.

The shear operating lever extends forwardly of the standard so as to cooperate with the shear lever 34. After the strap has been appropriately tightened the eccentric shaft lever is disengaged 30 from the eccentric shaft in the manner described heretofore and the shear lever 34 is rotated about the eccentric shaft and in a counter-clockwise direction as shown in Figures 1, 2 and 5 to the position indicated in chain lines in Figure 1. By 35 virtue of the fact that the shear lever comes in direct engagement with the shear operating lever 95 further movement of the shear lever will depress the shear operating lever 95 thereby forcing the top shear downwardly for shearing the coil 40 end of the strap from the remaining portion thereof.

The top shear 16 extends horizontally to a position beneath the vertically reciprocable sealing mechanism including the ram, the bending and crimping jaws, and the seal supports to be described hereinafter. The upper surface of this top shear is beveled as at 103 so as to permit this extension of the shearing edge beneath the vertically reciprocable mechanism. When this mechanism is lowered the seal support 140 strikes the beveled surface and continued downward movement of this mechanism cams the entire shearing mechanism to one side against the pressure of the spring 102 which normally urges the shear frame to the cutting position in which the upper shear extends beneath the vertically reciprocable mechanism. Upon raising and bending the crimping mechanism upon completion of the bending and crimping operation the shear 50 mechanism is again automatically returned to shearing position by the spring 102.

The mechanism for pressing the seal 61, which has been appropriately fed by the feeding mechanism, down on the strap and for bending and 55 crimping it and the overlapping strap ends includes a ram 104 which is reciprocable in suitable guides formed in the standard 3. The ram is reciprocated in the standard by means of a forming lever 105 pivotally mounted at 106 on 60 the standard. The forming lever 105 is provided with a slot 107 cooperating with a pin 108 carried by a ram operating link 109 which is pivotally mounted at 110 to the standard. This operating link, in turn, is provided with a slot 111 65

in which a ram pin 112 is mounted. The ram pin 112 extends through openings in the bifurcated upper end of the ram and as pressure is exerted on the ram pin by the forming lever 5 through the ram operating link, the ram is reciprocated in the standard.

The bending and crimping mechanism also includes jaws 113 which are adapted to be normally positioned above the seal when it is fed into 10 to position over the strap and to be moved downwardly against the projecting ends of the seal 61 and to bend these projecting ends downwardly around the overlapping strap ends. Upwardly extending side plates 114 are provided 15 on each end of each of the forming or bending jaws. The side plates are provided with openings 115 to receive the main operating pin 116. These plates are also provided with overlapping slots 117 adapted to receive the operating pin 20 118 which extends through an opening 119 in the ram. The main operating pin 116 also extends through a longitudinally extending slot 120 in the ram. The main operating pin 116 at each end extends beyond the side plates to the 25 forming jaws, and these ends cooperate with guides 121 and stop members 122.

The bending and crimping mechanism also includes a presser head 130 which is generally U-shaped having a bottom portion 131 and side members 132. The side members are provided with slots 133 to receive the main operating pin 116 and with slots 134 for receiving the inwardly projecting portion of the ram stop guide so that when the presser head has been moved downwardly to a sufficient extent to be brought into contact with the overlapping strap ends further downward movement thereof will be prevented.

The ram is provided with a longitudinally extending recess 135 which is adapted to receive a spring 136, the lower end of which bears against a 40 presser head thereby normally holding the ram in up-raised position. At the lower end the ram is provided with hardened tips 137 which, upon lowering of the ram, come in contact with the seal and the overlapping strap ends and crimp 45 the seal and the strap ends as indicated at 138 in Figures 10, 11 and 12. The presser head is provided with slots 139 to permit the hardened tips of the ram to pass therethrough and contact the seal.

Seal supports 140 made of flat spring steel are also associated with the bending and crimping mechanism and reciprocated therewith. A seal support is mounted on each side of the presser 55 head and extends downwardly around the lower end thereof, a horizontal tip being provided at the lower end of each seal support in order to receive and support a seal which is fed by the feeding mechanism into position above the overlapping strap ends and below the presser head. Each seal support is provided with an opening 141 adapted to receive the main operating pin 116. These opening or slots 141 extend longitudinally of the seal supports so as to permit the operating pin 116 to move relative to the seal supports upon the completion of the stroke of the seal supports. An opening 142 is also provided in each of the seal supports to receive the laterally projecting finger of the ram stop guide 70 121.

It is highly desirable that the seals fed into position below the presser head and above the superposed strap ends shall be accurately positioned. The seal supports will, of course, aid in properly positioning the seals but in order to as-

sure the proper positioning of the seals I propose to utilize seals which are provided with a center hole or recess 143 which will cooperate with a spring pressed pin 144 extending through the bottom of the presser head. A spring 145 is provided in the recess 143 in the ram for pressing the pin 144 downwardly through the opening in the presser head at all times. A shoulder 146 is provided on the pin for preventing it from passing completely through the opening in the presser head. The holes 143 in the seals serve another useful purpose. These holes can be used for proper stacking and shipping of the seals.

An adjustable stop pin 150 is mounted on the standard for limiting the movement of the forming lever 105.

As pointed out heretofore, keepers 17 and 18 are provided for properly alining the strap ends during operation of the device. The keeper 18 is operable manually and the keeper 17 is automatically actuated by a pin 151 carried by the shuttle lever 71. This pin 151 reciprocates in a slot 152 in the keeper 17.

In the operation of the device just described, the strap 10 is first disposed about the box 11. The shear lever 34 and the eccentric shaft lever 28 are rotated by the handle 36 in a counter-clockwise direction from the position marked I shown in solid lines to the position marked II shown in chain lines. During this period of time the handle 36 extends at right angles to the levers and by reason of the movement of the eccentric shaft lever, the toothed wheels 30 are brought into firm engagement with the overlapping strap ends. The tightening lever 45 is then raised to the position shown in chain lines and is reciprocated between that position and the position shown in solid lines for rotating the toothed tightening wheels for tightening the strap around the box. After the strap has been sufficiently tightened the handle 36 is raised from the position shown in solid lines in Figure 6 to the position shown in chain lines so as to disengage the eccentric shaft lever from the shaft. The handle 36 and the shear lever 34 are then moved from the position marked II in Figure 1 to the position marked III. During this operation the eccentric shaft is rotated thereby actuating the shuttle lever which, in turn, operates the feeding mechanism and feeds a seal to a position above the overlapping strap ends and immediately below the presser head, the seal being held in this position by means of the seal supports heretofore described. The shear lever then continues past the position marked III in Figure 1 and the shear lever 95 actuates the top shear and severs the coil end of the strap from the portion which is around the box.

The apparatus is then in proper position for the operation of the forming lever for forcing the seal down onto the strap ends and for bending it therearound and for crimping it. During initial movement of the forming lever 105 in a clockwise direction as shown in Figure 1, the spring latch 153 is disengaged and the ram operating link 109 caused to force the ram pin 112 and the ram downwardly. The ram pin 112 is provided with a reduced end portion 154 which cooperates with a forming lever latch 155, the reduced end portion of the ram pin extending into a small recess 156 in the latch. The latch is provided with roller pins 157 which cooperate with a slot 158 in the latch guide 159. The slot 158 at its lower end is turned at right angles to the main direction of travel of the rollers 157.

The latch 155 is provided with a protruding nose portion 160 adapted to bear against the main operating pin 116.

5 During the initial downward movement of the ram pin 112 the forming lever latch by the arrangement just described causes the main operating pin 116 to move downwardly with the ram. When the lower roller 157 of the forming lever latch reaches the lateral portion of the slot it 10 moves laterally and the ram pin reduced end is disengaged from the forming lever latch, and continued downward movement of the forming lever latch by reason of the operation of the ram pin 112 stops.

15 During the above-described operation the ram moves downwardly and by virtue of the connection between the ram and the main operating pin 116 through the ram pin and the forming lever latch, the main operating pin 116 and the jaws carried thereby are moved downwardly. The presser head and the seal supports likewise move downwardly with the main operating pin. During this operation the seal is brought into contact with the superposed strap ends and the jaws bend the seal downwardly past the edges of the strap. Further downward movement of the ram causes the operating pin 118 to continue in its downward movement and by reason of the overlapping slots in the jaws the jaws are pulled together for bending the seal inwardly around the strap. Further continued downward movement of the ram will cause the hardened tips 137 to pass through the openings in the forming lever guard and to crimp the seal and the strap ends. As has been stated before, the initial downward movement of the forming and crimping mechanism will force the shearing mechanism to one side against the pressure of the spring so as to permit the seal to extend over or adjacent to the sheared strap end.

After the forming operation has been completed, the forming lever 105 is raised and the spring forces the plunger and other operating parts upwardly into position for a repetition of the operation. During the upward movement of the ram pin it will engage the slot in the forming lever latch and pull the latch to the right as shown in Figure 4 and carry it upwardly in the operating slot 158.

45 50 It will be apparent from the foregoing description that the invention provides a device for expeditiously and effectively securing together the ends of a binding or reinforcing strap passing around a box or other container. It also will be apparent that the device is relatively simple in construction so that it can be manufactured comparatively cheaply and operated by unskilled labor. The device is compact and complete and at the same time is of such size that it can be readily handled by the workmen. The unitary device which I provide incorporates means for tightening and severing the strap, for feeding a flat clip blank or seal over the overlapped ends of the strap and for forming a joint between the 55 clip and the overlapped ends of the strap.

55 60 While I have shown and described herein a preferred embodiment of my invention, it will be recognized that changes in the construction disclosed can be made without departing from the 65 spirit of the invention or the scope of the appended claims.

I claim:

1. Apparatus for fastening together the ends of a binding strap and a clip seal comprising 70 means for tightening the strap and for holding 75

the strap ends in superposed relationship, vertically reciprocable means including forming jaws, a ram and a presser head for positioning a clip seal over the superposed strap ends and for forming the joint between the strap ends and the clip seal, feeding apparatus for feeding a clip seal over the superposed strap ends and below said reciprocable means, and at least one seal support carried by said vertically reciprocable means for supporting the seal above the strap ends and below the vertically reciprocable means. 10

2. Apparatus for fastening together the ends of a binding strap and a clip seal comprising means for tightening the strap and for holding the strap ends in superposed relationship, vertically reciprocable means including forming jaws, a ram and a presser head for positioning a clip seal over the superposed strap ends and for forming the joint between the strap ends and the clip seal, feeding apparatus for feeding a clip seal over the superposed strap ends and below said reciprocable means, at least one seal support carried by said vertically reciprocable means for supporting the seal above the strap ends and below the vertically reciprocable means, and stop 20 means for stopping the downward movement of the seal support prior to the termination of the downward stroke of the vertically reciprocable means. 25

3. Apparatus for fastening together the ends of a binding strap and a clip seal comprising means for tightening the strap and for holding the strap ends in superposed relationship, sealing mechanism including bending jaws for forming the joint between the strap ends and the clip seal, a reciprocable shuttle for feeding a clip seal to a position beneath the sealing mechanism, a shuttle lever for operating the shuttle through a feeding stroke and upon completion of the feeding stroke through a return stroke, means operable at the end of the feeding stroke to move the shuttle lever into operative position with respect to the shuttle for moving the same through the return stroke, and means for actuating the shuttle lever. 40

4. Apparatus for fastening together the ends of a binding strap and a clip seal comprising means for tightening the strap and for holding the strap ends in superposed relationship, sealing mechanism including bending jaws for forming the joint between the strap and the clip seal, a reciprocable shuttle for feeding a clip seal to a position beneath said sealing mechanism, the shuttle having an L-shaped recess therein extending through the rear end thereof, a shuttle lever positioned in said recess and arranged to cooperate with the shuttle to move it in one direction only until after the completion of the feeding stroke of the shuttle, means for moving the shuttle lever at the end of the feeding 50 stroke of the shuttle upwardly into the recess so as to prevent return movement of the shuttle lever without the shuttle, means for reciprocating the shuttle lever, and a shuttle guard, said guard having a shoulder portion adapted to lower the shuttle lever at the end of the return stroke of the shuttle to position it to actuate the shuttle in one direction only. 55

5. Apparatus for fastening together the ends of a binding strap and a clip seal comprising means for tightening the strap and for holding the strap ends in superposed relationship, sealing means for forming the joint between the strap ends and the clip seal, feeding apparatus for feeding a clip seal over the superposed strap ends adjacent 60

the sealing mechanism, a movably mounted shear for severing the upper strap adjacent the point of sealing, and means for actuating the shear, said movably mounted shear being normally positioned beneath said sealing mechanism and having a cam surface adapted to cooperate with the sealing mechanism to permit the sealing mechanism to cam the shear away from the joint upon downward movement of the sealing mechanism.

10. 6. Apparatus for fastening together the ends of a binding strap and a clip seal comprising means for tightening the strap and for holding the strap ends in superposed relationship, sealing mechanism including bending jaws for forming 5
15 the joint between the strap ends and the clip seal, feeding apparatus for feeding a clip seal over the superposed strap ends and adjacent the sealing mechanism, a movably mounted shear including a shear block and an upper shear member for 20
20 severing the upper strap adjacent the point of sealing, and means for actuating the shear, said movably mounted shear being automatically cammed out of cutting position adjacent the point of sealing upon actuation of the sealing 25
25 mechanism.

7. Apparatus for fastening together the ends of a binding strap and a clip seal comprising means for tightening the strap and for holding the strap ends in superposed relationship, sealing 30
30 mechanism for forming the joint between the strap ends and the clip seal, feeding apparatus for feeding the clip seal over the superposed strap ends and adjacent the sealing mechanism, a movably mounted shear including a shear block 35
35 and an upper shear member for severing the upper strap adjacent the point of sealing, spring means for normally urging the shear toward shearing position, and means for actuating the shear, said movably mounted shear extending beneath the sealing mechanism when in normal 40
40 position and cooperating with said sealing mechanism so that upon movement of the sealing mechanism to sealing position the shear will be moved thereby away from the point of sealing.

8. Apparatus for fastening together the ends 45
45 of a binding strap and a clip seal comprising means for tightening the strap and for holding the strap ends in superposed relationship, vertically reciprocable sealing mechanism for forming the joint between the strap ends and the 50
50 clip seal, feeding apparatus for feeding a clip seal above the superposed strap ends and adjacent the sealing mechanism, a movably mounted shear including a shear block and an upper shear mem-

ber for severing the upper strap adjacent the point of sealing, means for normally urging the shear to a position beneath said sealing mechanism, said shear having a cam surface for co-operation with the sealing mechanism whereby movement of the sealing mechanism to sealing position will automatically move the shear out of position beneath the sealing mechanism, means for actuating the sealing mechanism and means for actuating the shear. 10

9. Apparatus for fastening together the ends of a binding strap and a clip seal comprising means for tightening the strap and for holding the strap ends in superposed relationship, sealing mechanism including bending jaws for forming 15
15 the joint between the strap ends and the clip seal, a reciprocable shuttle for feeding a clip seal to a position adjacent the sealing mechanism, a reciprocable shuttle lever for moving the shuttle through a feeding stroke and upon completion of the feeding stroke through a return stroke, said shuttle lever and shuttle being arranged so that the lever may be moved into and out of operative engagement with the shuttle, means operable at approximately the end of the feeding stroke for 20
20 moving the shuttle lever to operative position with respect to the shuttle to move it through the return stroke, and means for moving the shuttle lever into a position where it is inoperative to move the shuttle through a return stroke 25
25 until the completion of the succeeding feeding stroke.

10. Apparatus for fastening together the ends of a binding strap and a clip seal comprising means for tightening the strap and for holding 30
30 the strap ends in superposed relationship, sealing mechanism including bending jaws for forming a joint between the strap ends and the clip seal, a reciprocable shuttle for feeding a clip seal to a position adjacent the sealing mechanism, a shuttle lever for operating the shuttle through a feeding stroke and through a return stroke, means for moving the shuttle lever into inoperative position with respect to the shuttle and the movement thereof through the return stroke, whereby the 35
35 shuttle cannot be moved through a return stroke until the shuttle lever is again moved to operative position, means for moving the shuttle lever at the end of the feeding stroke into operative position with respect to the shuttle for moving it through the return stroke, and means for actuating the shuttle lever. 40
